UNITED STATES PATENT OFFICE

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY

SUPERHEATER BOILER

Application filed July 20, 1922, Serial No. 576,183. Renewed July 5, 1929.

My present invention relates to steam boilers provided with superheaters and will be best understood from the following description and the annexed drawings, in which Fig. 1 is a vertical sectional elevation of a well-known type of water-tube boiler which I have adapted for purposes of illustration and embodying my invention; Fig. 2 is a partial view similar to Fig. 1 and showing a modification; Fig. 3 is a section similar to Fig. 1 and showing another arrangement of my invention; Fig. 4 is a section on the line 4-4 of Fig. 3, and Fig. 5 is a vertical section of another type of boiler in which I have embodied my invention.

Like reference characters indicate like parts in the several views.

Referring first to the form of my invention shown in Fig. 1, the illustrative type of boiler has uptake headers 10 and downtake headers 11 connected to a steam and water drum 12, the headers being connected by horizontally inclined water tubes in rows in the usual manner and divided into an upper bank 13 and a lower bank 14 with a space between the banks. A longitudinal baffle 15 extends from the downtake headers 11 along the lowermost row of water tubes toward the uptake headers 10 but stopping short thereof to form a gas passage. Above the lowermost row of tubes in the upper bank 13 is a longitudinal baffle 16 located between the headers and spaced from each of them. From the left-hand end of the baffle 16 is a cross baffle 17 and cross baffles 18 and 19 are also provided, the latter extending vertically from the right-hand end of the baffle 16 and the baffle 18 extending part way down across the upper bank of tubes in the usual manner. A main gas outlet 20 is provided and plates 21 and 22 form a flue from the space between the baffles 18 and 19 to this gas outlet. A damper 23 controls an opening between the pass formed by the headers 11 and the cross baffle 19 and the flue leading to the main gas outlet 20.

In the space between the banks of tubes and between the baffles 15 and 16 is a superheater which, in the form illustrated, is of the usual U-tube type having tubes 24 connected to

headers 25 and 26. The superheater tubes are shown supported by rods 27, 28 connected to the lower end of the cross-baffle 18. Saturated steam from the drum 12 passes through the curved pipe 26' (the upper curve of which is broken away in Fig. 1) to the inlet header 26, and thence through the superheater tubes to the outlet header 25 and its outlet connection 25'. A separate saturated steam outlet 12' having a valve 13' may be provided in the drum 12.

The furnace gases are directed by the baffle 15 toward the ends of the tubes adjacent the uptake headers 10 and if the damper 23 is closed, they will all pass upward through the pass defined by the baffle 17 and the headers 10 and thence back and forth across the upper bank 13 to the main gas outlet 20, the last pass being between the baffles 18 and 19. If the damper 23 is opened, then some of the gases, depending on the degree to which the damper 23 is opened, will pass into the space between the baffles 15 and 16 across the entire width of the boiler from the left-hand end thereof down across the superheater tubes 24 and out of the chamber formed between the baffles 15 and 16 through the space between the right-hand end of the baffle 16 and the down take headers 11 and from thence across the lower ends of the upper bank of water tubes past the damper 23 to the gas outlet.

Preferably, the baffles 15 and 16 will extend entirely across the boiler setting, so that the gases which flow through the superheater chamber are taken from the entire width of the furnace, so that there is no unbalancing which might occur if the gases were taken from one side only or from a given portion widthwise of the furnace. By operating the damper 23, the quantity of gases which will flow over the superheater may be regulated so that the degree of superheat may be controlled.

In the operation of a steam boiler having a superheater, some of the steam generated may be drawn from the boiler without passing through the superheater. Without provision for this condition, the temperature of the superheated steam at a given rating

would be higher than if all of the steam generated passed through the superheater, and if the proportion of saturated steam thus by-passed around the superheater becomes too great, it may result in the burning out of the superheater. By the arrangement which I have provided, this may be prevented by regulating the amount of gases passing over the superheater in accordance with 10 the proportion of saturated steam being drawn directly from the boiler. Thus, in the arrangement of Fig. 1, if the quantity of saturated steam drawn directly from the boiler through the outlet 12' by opening 15 the valve 13' is increased, then the damper 23 may be turned by hand in the usual manner, to decrease the flow of hot gases over the superheater and through the pass between the baffle 19 and the headers 11 and 20 correspondingly decrease the heat delivered to the smaller quantity of steam flowing through the superheater.

Figure 2 shows the arrangement if the gas outlet 20 is arranged so that the gases 25 pass off between the nipples connecting the downtime headers 11 and the steam and water drum 12. The damper 23' controls the flow of gases over the superheater as described in connection with Fig. 1, and the 30 damper 29 is the usual damper provided for the gases passing over water tubes.

In Figs. 3 and 4, I have shown an arrangement similar to that shown in Fig. 1, but with the superheater arranged so as to 35 have its tubes extending crosswise of the water tubes. The arrangement of baffles, dampers and the like are the same as in Fig. 1 and it will be unnecessary to re-describe them. The headers 25 and 26 in the form 40 shown in Fig. 3 are located outside of the boiler setting and preferably are arranged as shown, with the headers and tubes duplicated on either side so that long U-tubes are avoided. Preferably, the headers 25 and 45 26 are provided with partitions, as at 251 and 261, so that the steam entering the inlet header 25 passes through the group of tubes 24 at the right of Fig. 3 to the header 26, thence back through the middle group 50 of tubes 24 to the header 25 and finally back to the outlet header 26 through the left-hand group of tubes 24. The gases flow through the superheater chamber longitudinally of the water tubes in a direction from 55 left to right in Fig. 3 and, since the steam in the superheater is flowing from right to left, the steam is flowing counter to the gas flow, so that the steam flows first through tubes which come in contact with the coolest 60 gases and thence successively through tubes contacted by hotter gases, the last superheater tubes being contacted by the hottest gases.

In the arrangement shown in Fig. 5, the 65 uptake headers 30 and downtime headers 31

are connected by horizontally inclined water tubes divided into two banks, the lower bank in this form consisting of four rows of tubes 34, with the top row spaced from the others. A baffle 35 extends along the first row of the tubes 34 from the downtime headers 31 toward the uptake headers 30. Below the lowermost row of the upper bank 33 is a longitudinal baffle 36 spaced from the downtime headers 31 to provide a gas passage. The cross baffle 37 is inclined to provide a gradually restricted pass across the right-hand end of the tubes 33 and vertical baffles 38 and 39 provide cross passes, the last pass leading to the main gas outlet 40.

Above the first and second passes of the main bank of water tubes 33 is a primary superheater having U-tubes 41 connected to cross headers in the usual way, these headers being connected to the steam and water drum 32. In the space between the baffles 35 and 40

36 is a secondary superheater having superheater tubes 42, also connected to headers extending across the boiler. The inlet header of the lower superheater is connected by a pipe 43 with the outlet header of the upper superheater. A damper 44 is provided in the gas pass formed by the baffle 39 and the downtime headers 31. The boiler is illustrated as

fired by a chain-grate stoker, the gases from which pass upward and are directed by the baffle 35 into the pass formed between the baffle 37 and the uptake headers 30 from whence they flow over the upper or primary superheater and then back and forth across the upper bank of tubes, the last pass upward being between the cross baffles 38 and 39 to the gas outlet 40. If the damper 44 is closed, all of the gases follow the path indicated. If, on the other hand, the damper 44 is open, then some of the gases, in a ratio determined by the amount of opening of the damper will pass into the space between the baffles 35 and 40 and from thence into the last vertical pass at the left of Fig. 5, and past the damper 44 to the main gas outlet. In the arrangement described, the regulation of the damper 44 will control the degree of superheat to be obtained in the secondary superheater. The steam from the steam and water drum 32 will first be superheated in the primary superheater 41 by gases which are of comparatively low temperature because of their having passed once across the entire bank of tubes.

The steam from the primary superheater will then pass into the secondary superheater where the temperature of the steam will be raised by the hot gases taken substantially directly from the furnace and passed over the superheater tubes 42, the quantity of these gases being regulated by the damper 44.

In each embodiment of my invention, it will be seen that the gases passing over the superheater located among the water tubes

130

are taken from the entire width of the furnace chamber, so that there is no unbalancing effect, no matter to what degree the flow of these gases may be regulated. It will also be observed that the gases from the superheater chamber, which, of course, will have considerable heat therein, will flow uniformly over the ends of all of the water tubes, so that there is no tendency to heat the tubes on one side of the boiler differently from those on the other side, as might be the case if all of the gases from the superheater chamber are directed against some of the tubes at one side of the boiler only. By the arrangement shown in Fig. 5, a large amount of superheating surface may be supplied for the primary superheating of the steam, and then a relatively small amount subjected to relatively hot gases will raise the steam to the desired degree of superheat which may be controlled by the damper 44.

It will be understood by those skilled in the art, that all of the dampers shown in the illustrative embodiments may be operated from the exterior of the boiler in the manner commonly used.

While preferably the water chambers at each end of the water tubes are made up of a plurality of headers, it will be understood that each set of headers functions as a water chamber and that I may use a single water chamber instead of a set of headers. In the annexed claims, therefore, it should be understood that I use the term "water chamber" to describe one of the water boxes connected to the water tubes, whether such water box is made up of a plurality of headers or is one continuous chamber.

While I have shown my invention applied to boilers of certain type, it will be understood that its application may be widely varied.

I claim:—

1. In combination, a water-tube boiler having rows of horizontally inclined water tubes connected at either end by water chambers, a main gas outlet, a superheater located between some of the rows of said tubes, a longitudinal baffle arranged to compel all of the gases to flow from the furnace toward the high ends of the water tubes and a set of baffles to direct some of the gases from the furnace back and forth across the tubes to the main gas outlet, some of the baffles of said set being also arranged to direct the remainder of the gases over the superheater in a direction longitudinal of the water tubes and then to the main gas outlet.

2. In combination, a water-tube boiler having rows of horizontally inclined water tubes connected at either end by water chambers, a main gas outlet, a superheater located between some of the rows of said tubes, a longitudinal baffle arranged to compel all of the gases to flow from the furnace toward the

high ends of the water tubes and a set of baffles to direct some of the gases from the furnace back and forth across the tubes to the main gas outlet, some of the baffles of said set being also arranged to direct the remainder of the gases over the superheater in a direction longitudinal of the water tubes and then to the main gas outlet, and a damper to regulate the flow of gases over the superheater.

3. In combination, a water-tube boiler having rows of horizontally inclined water tubes connected at either end by water chambers, a main gas outlet, a superheater chamber between some of the rows of water tubes and extending from side to side of the boiler, a superheater in said chamber, baffles to direct some of the furnace gases over water tube surface only to the main gas outlet and the superheater chamber having an inlet opening at the end away from the low ends of the water tubes and substantially as wide as the boiler and an outlet flue at the end adjacent the low ends of the tubes and leading to the main gas outlet, whereby the remainder of the furnace gases may pass through the chamber in a direction longitudinal of the water tubes, and a damper to regulate the flow of gases through said chamber, the gases that have flowed over the superheater to the gas outlet being independent of those flowing over the boiler tubes beyond said superheater.

4. In combination, a water-tube boiler having rows of horizontally inclined water tubes connected at either end by water chambers, a main gas outlet, a primary superheater located above the tubes, a secondary superheater located between some of the rows of tubes and connected to the primary superheater, baffles to direct some of the furnace gases over water tube surface and the primary superheater to the main gas outlet, and means to direct a regulated portion of the furnace gases over the secondary superheater to the main gas outlet.

5. A water-tube boiler having a primary superheater located in a relatively cool zone and a secondary superheater located in a relatively hot zone connected together in series with reference to the flow of steam, and means to direct a portion of the furnace gases over the primary superheater and another portion over the secondary superheater.

6. A water-tube boiler having a primary and a secondary superheater connected together and to the boiler, means to direct a portion of the furnace gases over the primary superheater and another portion over the secondary superheater, and means whereby the ratio of the two portions may be regulated.

7. A water-tube boiler having a primary and a secondary superheater connected together and to the boiler, and means to direct

a portion of the furnace gases over the primary superheater and another portion over the secondary superheater, the boiler and the superheaters being arranged so that the path of the gases from the boiler furnace to the primary superheater has more of the boiler tubes therein than the path of the gases from the boiler furnace to the secondary superheater, whereby the secondary superheater will be subjected to the hotter gases.

8. A water-tube boiler having a primary and a secondary superheater connected together and to the boiler, means to direct a portion of the furnace gases over the primary superheater and another portion over the secondary superheater, and means whereby the ratio of the two portions may be regulated, the boiler and the superheaters being arranged so that the path of the gases from the boiler furnace to the primary superheater has more of the boiler tubes therein than the path of the gases from the boiler furnace to the secondary superheater, whereby the secondary superheater will be subjected to the hotter gases.

9. A water tube boiler having a primary and secondary superheater, at least one of which is located within the boiler setting, said superheaters being connected in tandem with the steam passing from the steam drum through one superheater to the other superheater, and means for varying the flow of gases over at least one of said superheaters.

10. In combination, a water tube boiler having a bank of tubes arranged in rows and connected at either end by water chambers, a main gas outlet, a superheater located between some of the rows of said tubes, a longitudinal baffle arranged to compel all of the gases to flow from the furnace toward one end of said bank, a set of baffles to direct a portion of the gases from the furnace back and forth across the tubes of said bank and towards said main gas outlet, some of the baffles of said set being also arranged to direct another portion of the gases over the superheater in a direction longitudinal of the water tubes and then to the main gas outlet, and a damper to regulate the flow of gases over the superheater.

11. In combination, a water tube boiler having rows of horizontally inclined water tubes connected at either end by water chambers, a main gas outlet, a primary superheater located above the tubes, a secondary superheater located between some of the rows of tubes and connected in series with the primary superheater, baffles to direct some of the furnace gases over water tube surface and the primary superheater to the main gas outlet, and means to direct a regulated portion of the furnace gases over the secondary superheater to the main gas outlet.

12. A water tube boiler having a primary superheater connected to the boiler and a

secondary superheater connected in series with the primary superheater, and means to direct a portion of the furnace gases over the primary superheater and from thence to the boiler waste gas outlet without contacting with the secondary superheater, and to direct the remainder of the furnace gases over the secondary superheater and from thence to the gas outlet without contacting with the primary superheater, the boiler and the superheaters being arranged so that the secondary superheater will be subjected to the hotter gases.

13. A water tube boiler having a primary superheater connected to the boiler and a secondary superheater connected in series with the primary superheater, means to direct a portion of the furnace gases over the primary superheater and from thence to the boiler waste gas outlet without contacting with the secondary superheater, and to direct the remainder of the furnace gases over the secondary superheater and from thence to the gas outlet without contacting with the primary superheater, and means whereby the ratio of the two portions of gas may be regulated, the boiler and the superheaters being arranged so that the secondary superheater will be subjected to the hotter gases.

14. A water tube boiler having a plurality of superheaters arranged in tandem relation, both said superheaters being subjected to heat from the same source and one of said superheaters being in a more highly heated region than another, and means for varying the amount of heat received by at least one of said superheaters.

15. A water tube boiler having a plurality of superheaters located within the boiler setting and arranged in tandem relation to each other, one of said superheaters being in a more highly heated region than another, and means for varying the amount of heat received by at least one of said superheaters.

16. A water tube boiler having a plurality of superheaters arranged in tandem relation to each other with one superheater in a hotter region than another, all of said superheaters being located within the boiler setting, and a control device for varying the amount of heat received by the superheater which is in the hotter region.

17. A water tube boiler having a plurality of superheaters subjected to heat from the same source of heat and arranged in tandem relation, at least one of said superheaters being located in the boiler setting, one of said superheaters being in a bypass around some of the boiler heating surface, and a control device arranged to control the gas flow through said bypass.

18. A water tube boiler having a plurality of superheaters subjected to heat from the same source of heat and arranged in tandem relation, one of said superheaters being in a

- bypass around some of the boiler heating surface, and a single control device arranged to simultaneously increase the gas flow over the superheater in the bypass and decrease the gas flow over the other superheater. 5
19. A water tube boiler having a primary superheater connected to the boiler and a secondary superheater connected in series with the primary superheater, at least one of said superheaters being located in a zone of greater heat than the other, means to direct a portion of the furnace gases over the primary superheater and from thence to the boiler waste gas outlet without contacting with the secondary superheater, and to direct the remainder of the furnace gases over the secondary superheater and from thence to the gas outlet without contacting with the primary superheater, and means whereby the ratio of the two portions of gas may be regulated. 10
20. A water tube boiler having a primary and a secondary superheater connected together and to the boiler, and means to direct a portion of the furnace gases at a relatively low temperature over the primary superheater and the remainder at a relatively high temperature over the secondary superheater only and longitudinally of said secondary superheater. 15
21. A water tube boiler having a primary and a secondary superheater connected together and to the boiler, at least one of said superheaters being located in a zone of greater heat than the other, means to direct a portion of the furnace gases over the primary superheater and the remainder over the secondary superheater to the exclusion of the primary superheater, and means to regulate the ratio of gases passing over the respective superheaters. 20
22. A water tube boiler having a primary and a secondary superheater connected together and to the boiler, at least one of said superheaters being located in a zone of greater heat than the other, and means to direct a portion of the furnace gases over the primary superheater and the remainder over the secondary superheater only, or to direct all of said gases over the primary superheater. 25
23. A water tube boiler having a first and a second superheater connected thereto and connected together in series with respect to the flow of steam, at least one of said superheaters being located in a zone of greater heat than the other, and means to direct a portion of the furnace gases over the first superheater and the remainder over the second superheater to the exclusion of the first, or to direct all of said gases over one of said superheaters. 30
24. A water tube boiler comprising two superheaters connected together in series with reference to the flow of steam, one of said superheaters being located in a relatively cool zone and the other in a relatively hot zone, and means to direct one portion of the furnace gases over one of said superheaters, and another portion over the other superheater. 35
25. In a steam boiler, a primary superheater located in a relatively cool zone and connected to and receiving steam from said boiler, a secondary superheater located in a relatively hot zone and connected in series with said primary superheater with reference to the flow of steam, the gases flowing over both the primary and the secondary superheaters, and means whereby the ratio of the gases flowing over the respective superheaters may be varied. 40
26. In combination, a water tube boiler having rows of horizontally inclined water tubes connected at either end by water chambers, a main gas outlet, a superheater, means for directing a portion of the main gas stream over boiler tubes to the gas outlet, and means for directing another portion of the gases over the superheater to said gas outlet and independently of said first-named portion of the gas stream, the entrance for the gases to the superheater extending from side to side of the boiler. 45
27. In combination, a water tube boiler having rows of horizontally inclined water tubes connected at either end by water chambers, a main gas outlet, a superheater located between some of the rows of said tubes, means for directing a portion of the main gas stream over boiler tubes to the gas outlet, and means for directing another portion of the gases over the superheater to said gas outlet and independently of said first-named portion of the gas stream, the entrance for the gases to the superheater extending from side to side of the boiler. 50
28. In combination, a water tube boiler having rows of horizontally inclined water tubes connected at either end by water chambers, a main gas outlet, a superheater, means for directing a portion of the main gas stream over boiler tubes to the gas outlet, and means for directing another portion of the gases over the superheater to said gas outlet and independently of said first-named portion of the gas stream, and means for varying the relative amounts of gases flowing over said boiler tubes and over said superheater, the entrance for the gases to the superheater extending from side to side of the boiler. 55
29. In combination, a water tube boiler having rows of horizontally inclined water tubes connected at either end by water chambers, a main gas outlet, a superheater, means for directing a portion of the main gas stream over boiler tubes to the gas outlet, means for directing another portion of the gases over the superheater to said gas outlet and independently of said first-named portion of the gas stream, and a damper for 60
30. In combination, a water tube boiler having rows of horizontally inclined water tubes connected at either end by water chambers, a main gas outlet, a superheater, means for directing a portion of the main gas stream over boiler tubes to the gas outlet, and means for directing another portion of the gases over the superheater to said gas outlet and independently of said first-named portion of the gas stream, and a damper for 65
31. In combination, a water tube boiler having rows of horizontally inclined water tubes connected at either end by water chambers, a main gas outlet, a superheater, means for directing a portion of the main gas stream over boiler tubes to the gas outlet, and means for directing another portion of the gases over the superheater to said gas outlet and independently of said first-named portion of the gas stream, and a damper for 70
32. In combination, a water tube boiler having rows of horizontally inclined water tubes connected at either end by water chambers, a main gas outlet, a superheater, means for directing a portion of the main gas stream over boiler tubes to the gas outlet, and means for directing another portion of the gases over the superheater to said gas outlet and independently of said first-named portion of the gas stream, and a damper for 75
33. In combination, a water tube boiler having rows of horizontally inclined water tubes connected at either end by water chambers, a main gas outlet, a superheater, means for directing a portion of the main gas stream over boiler tubes to the gas outlet, and means for directing another portion of the gases over the superheater to said gas outlet and independently of said first-named portion of the gas stream, and a damper for 80
34. In combination, a water tube boiler having rows of horizontally inclined water tubes connected at either end by water chambers, a main gas outlet, a superheater, means for directing a portion of the main gas stream over boiler tubes to the gas outlet, and means for directing another portion of the gases over the superheater to said gas outlet and independently of said first-named portion of the gas stream, and a damper for 85
35. In combination, a water tube boiler having rows of horizontally inclined water tubes connected at either end by water chambers, a main gas outlet, a superheater, means for directing a portion of the main gas stream over boiler tubes to the gas outlet, and means for directing another portion of the gases over the superheater to said gas outlet and independently of said first-named portion of the gas stream, and a damper for 90
36. In combination, a water tube boiler having rows of horizontally inclined water tubes connected at either end by water chambers, a main gas outlet, a superheater, means for directing a portion of the main gas stream over boiler tubes to the gas outlet, and means for directing another portion of the gases over the superheater to said gas outlet and independently of said first-named portion of the gas stream, and a damper for 95
37. In combination, a water tube boiler having rows of horizontally inclined water tubes connected at either end by water chambers, a main gas outlet, a superheater, means for directing a portion of the main gas stream over boiler tubes to the gas outlet, and means for directing another portion of the gases over the superheater to said gas outlet and independently of said first-named portion of the gas stream, and a damper for 100
38. In combination, a water tube boiler having rows of horizontally inclined water tubes connected at either end by water chambers, a main gas outlet, a superheater, means for directing a portion of the main gas stream over boiler tubes to the gas outlet, and means for directing another portion of the gases over the superheater to said gas outlet and independently of said first-named portion of the gas stream, and a damper for 105
39. In combination, a water tube boiler having rows of horizontally inclined water tubes connected at either end by water chambers, a main gas outlet, a superheater, means for directing a portion of the main gas stream over boiler tubes to the gas outlet, and means for directing another portion of the gases over the superheater to said gas outlet and independently of said first-named portion of the gas stream, and a damper for 110
40. In combination, a water tube boiler having rows of horizontally inclined water tubes connected at either end by water chambers, a main gas outlet, a superheater, means for directing a portion of the main gas stream over boiler tubes to the gas outlet, and means for directing another portion of the gases over the superheater to said gas outlet and independently of said first-named portion of the gas stream, and a damper for 115
41. In combination, a water tube boiler having rows of horizontally inclined water tubes connected at either end by water chambers, a main gas outlet, a superheater, means for directing a portion of the main gas stream over boiler tubes to the gas outlet, and means for directing another portion of the gases over the superheater to said gas outlet and independently of said first-named portion of the gas stream, and a damper for 120
42. In combination, a water tube boiler having rows of horizontally inclined water tubes connected at either end by water chambers, a main gas outlet, a superheater, means for directing a portion of the main gas stream over boiler tubes to the gas outlet, and means for directing another portion of the gases over the superheater to said gas outlet and independently of said first-named portion of the gas stream, and a damper for 125
43. In combination, a water tube boiler having rows of horizontally inclined water tubes connected at either end by water chambers, a main gas outlet, a superheater, means for directing a portion of the main gas stream over boiler tubes to the gas outlet, and means for directing another portion of the gases over the superheater to said gas outlet and independently of said first-named portion of the gas stream, and a damper for 130

regulating the relative amounts of gases flowing over said boiler tubes and over said superheater, the entrance for the gases to the superheater extending from side to side of the boiler.

5 30. In combination, a water tube boiler having rows of horizontally inclined water tubes connected at either end by water chambers, a main gas outlet, a superheater located
10 between some of the rows of said tubes, means for directing a major portion of the main gas stream beyond said superheater back and forth across boiler tubes to said gas outlet, means for directing a minor portion
15 of the gases over the superheater to said gas outlet and independently of said major portion of the gas stream, and means for varying the relative amounts of gases flowing over said boiler tubes and over said
20 superheater, the entrance for the gases to the superheater extending from side to side of the boiler.

25 31. In combination, a water tube boiler having rows of horizontally inclined water tubes connected at either end by water chambers, a main gas outlet, a superheater, means for directing the main gas stream over boiler tubes, the main stream then dividing, the major portion thereof flowing back and forth
30 over other boiler tubes to the main gas outlet, and a minor portion thereof flowing over the superheater to the main boiler outlet and independently of the said major portion, and means for varying the relative
35 amounts of gases flowing over said boiler tubes and over said superheater, the entrance for the gases to the superheater extending from side to side of the boiler.

40 32. In combination, a water tube boiler having rows of horizontally inclined water tubes connected at either end by water chambers, said rows being divided into banks with a space between the banks, a superheater located in said space and at one end thereof, a main gas outlet, a longitudinal baffle extending from one of the water chambers along the tubes below the superheater and arranged to compel all of the gases to flow from the furnace toward the high ends of the water
45 tubes, baffles including cross baffles and a longitudinal baffle extending along the water tubes above the superheater to direct some of the gases back and forth across the water tubes to the main gas outlet, the main gas stream flowing over boiler tubes and then dividing, a major portion flowing back and forth across the remaining boiler tubes to
50 said gas outlet, and a minor portion flowing over the superheater to the main gas outlet and independently of the portion flowing back and forth across boiler tubes.

DAVID S. JACOBUS.
